FRINGE FORMING APPARATUS

Gertrudis Manzano, Landisville, N. J.

Application February 14, 1950, Serial No. 144,124

3 Claims. (Cl. 139—33)

1

My invention relates to a method of and apparatus for forming fringe. A primary object of the invention is to provide a highly simplified method of and apparatus for forming yarn fringe, or trimming in the desired lengths without the use of a sewing machine or other expensive device.

A further object is to provide a highly simplified device which facilitates the forming of the yarn fringe or trimming by hand, the device being very easy to operate, and well adapted for use in the home.

A further important object of the invention is to provide a method of and apparatus for weaving fringe or trimming which may be sold as a completed article of manufacture, the fringe having a variety of uses.

A still further object of the invention is to provide a fringe forming device which will be very cheap to manufacture and light weight in construction.

Other objects and advantages of the invention will be apparent during the course of the following description.

In the accompanying drawings forming a part of this application, and in which like numerals are employed to designate like parts throughout the same:

Figure 1 is a plan view of a fringe forming device embodying my invention and illustrating the use of the same;

Figure 2 is a central, vertical, longitudinal, sectional view taken on line 2—2 of Figure 1;

Figure 3 is a sectional view similar to Figure 2, and illustrating different operative positions of the fringe binding warps;

Figure 4 is a transverse, vertical, sectional view taken on line 4—4 of Figure 1; and

Figure 5 is an enlarged fragmentary plan view of a section of completed fringe or trimming made in the practice of my method.

In the drawings, where, for the purpose of illustration, is shown a preferred embodiment of the invention, the numeral 10 designates a rectangular frame including thin, longitudinal side-walls or sides 11 and thin, opposed, transverse ends or endwalls 12 connecting the opposite ends of the sides 11. The frame 10 is open at its bottom, and the sides 11 are somewhat longer than the ends 12, as shown clearly in Figure 1. A plurality of narrow, longitudinally elongated, transversely spaced slats 13 are rigidly secured to the top of the frame 10, and extend between the ends 12 thereof. The slats 13 are parallel and transversely spaced apart equidistantly for

2

forming narrow, longitudinal slots or passages 14 between them. As shown in Figure 1, one outermost slat 13 is disposed adjacent to one of the sides 11, while the opposite outermost slat 13 is spaced laterally inwardly of the opposite side 11 for forming a relatively wide slot or passage 15. Each slat 13 is provided near its longitudinal center with a small hole 16 disposed at the transverse center of the slat, and these holes 16 are arranged in transverse alignment, Figure 1.

The sides 11 of the frame are provided at their longitudinal and vertical centers with aligned, transverse openings 17, within which is journaled a transverse, rotatable spindle or shaft 18 which is disposed below the slats 13 and extending at right angles thereto. As shown in Figure 1, the openings 17 of the slats are spaced slightly beyond one side of the spindle 18. One end 19 of the spindle projects laterally outwardly of the adjacent frame side 11 for a substantial distance, to provide a handle for turning the spindle. A flat, circular disc 20 is keyed or otherwise rigidly secured to the spindle 18 adjacent to the inner face of the side 11 nearest to the end 19, Figure 4, and this disc is provided with a plurality of circumferentially spaced holes 21, adapted to be brought into registration with a similar hole 22 formed in the adjacent side 11 below the spindle 18. A removable locking pin 23 is provided, and extends through the hole 22 and through any selected hole 21 of the disc 20, for releasably locking the spindle 18 in a selected, adjusted position. The opposite end of the spindle 18 preferably terminates near and outwardly of the frame side 11 remote from the disc 20. The wide slot 15 affords ready access to the top of the disc 20 by the fingers.

A generally inverted U-shaped bracket 24 is preferably rigidly secured at one end to the outer face of one frame end 12 at the transverse center of such end, and the other end of the bracket 24 carries an adjustable clamp screw 24', so that the frame 10 may be readily detachably mounted upon any fixed support 25, such as the back of a chair or the like. As shown in Figure 3 of the drawings, the frame 10 is disposed horizontally during use, but if desired, the frame may be mounted vertically or at any desired inclination which best suits the user. The frame 10 is preferably provided at its end 12 opposite the bracket 24 with a U-shaped handle 26 rigidly secured thereto adjacent to the bottom open side of the frame.

A plurality of separate warp or fringe binding threads 27 are wound upon the spindle 18, so

that their free ends may be pulled simultaneously for unwinding the warp threads from the spindle. The spindle 18 may be provided with a plurality of axially spaced grooves 28 for dividing the spindle into axially spaced sections or spools 29 which will aid in the winding of the individual warp threads 27 upon the spindle. The spool section 29 will serve as a visual guide for approximately limiting the length of the spindle upon which one of the individual warp threads is wound or spooled. As shown clearly in Figures 2 and 3, the warp threads 27 are wound upon the spindle 18 in the same direction, so that their free ends may be pulled from one side of the spindle 18 for unwinding the warp threads. The arrangement is such that every other warp thread 27 may be passed upwardly through one of the holes 16, while the other warp threads are passed upwardly through the slots 14. As shown in Figures 2 and 3, the holes 16 are disposed substantially vertically above or in tangential alignment with one side of the spindle having the warp threads wound thereon. Although I have illustrated four of the slats 13, providing four of the holes 16 and three of the warp threads 27 passing upwardly through three of the slots 14, I do not wish to limit the invention to this precise number of slats, holes and warp threads. It should be understood that any convenient number of separate warp threads 27 may be provided, and a corresponding number of slats 13 having the holes 16 formed therein may be provided.

The use of the apparatus in the practice of my method is as follows:

With the parts assembled as shown and described, and the frame 10 fixedly secured to the support 25, the pin 23 may be removed, so that the spindle 18 may be turned a sufficient distance for unwinding the desired lengths of the warp or binding threads 27. The warp threads 27 are extended above the tops of the slats 13 for the desired and convenient distance, and I have found that a length of approximately 8 inches above the slats 13 is adequate for starting the formation of the fringe or trimming.

To begin the formation of a fringe or trimming 30, a section 31 of suitable wool yarn or the like must be provided from a separate ball of yarn or the like. The free ends of the separate warp threads 27 are knotted together, as at 32, and the free end of the yarn section or strand 31 is also knotted or tied with the free ends of the warp threads, as at 33. The thus knotted or tied-together ends of the warp threads and yarn are now held in the left hand, so that the warp threads 27 are extended above the slats 13 and slightly tensioned. Before this is done, it is to be understood that the locking pin 23 must be re-inserted through one of the apertures 21. This prevents the spindle 18 from turning during the formation of the fringe 30. With the warp threads 27 and yarn strand 31 thus held in the left hand and extended above the slats 13, as previously stated, the warp threads are swung downwardly toward one of the frame ends 12, as shown in either of Figures 2 or 3, where the warp threads will become angularly disposed or downwardly diverging, due to the coaction of the openings 16 with the warp threads that pass through them. The openings 16 restrict the movement of the lower ends of the extended warp threads 27 which pass through them, while those which pass through the slots 14 are free to travel longitudinally

of the slots, and to cross and recross the warp threads in the holes 16, as all of the warp threads are swung from one end of the frame 10 to the other, Figures 2 and 3. When the warp threads 27 are swung toward either end of frame 10, Figure 2 or 3, a first fringe loop 34 is pulled between the separated, diverging warp threads 27, and the warp threads are now swung toward the opposite end 12 of the frame. During this swinging movement, the warp threads which extend through the holes 16 will cross the warp threads which travel through the slots 14. This will cause the inner ends 34' of the loop 34 to be bound between the crossed warp threads, as at 35. When the warp threads have been swung from a position similar to that shown in Figure 2 to a position similar to that shown in Figure 3, a second fringe loop 36 is pulled between the separated diverging warp threads 27, and the warp threads are now swung again to their positions in Figure 2. This will bind or weave together the inner ends of the loop 36, as shown at 37. A third loop 38 may now be pulled between the diverging warp threads 27, and the warp threads are now swung again toward the opposite end of the frame. As this process is repeated, any desired number of the loops may be formed and woven or bound together at their inner ends. When the fringe 30 reaches the desired length, the warp threads 27 and yarn strand 31 are cut and knotted together similar to the manner shown at 32 and 33. The fringe 30 can obviously be made in any desired length and color, and the lengths of the loops 34, 36, 38 can be varied, as desired. During the formation of the fringe, as described above, the pin 23 is periodically removed for unwinding additional lengths of the warp threads 27, as required. The completed fringe 30 constitutes an article of manufacture which has a wide variety of uses, such as for fringes of rugs or curtains.

It is to be understood that the form of the invention herewith shown and described is to be taken as a preferred example of the same, and that various changes in shape, size and arrangement of parts may be resorted to without departing from the spirit of my invention or the scope of the subjoined claims.

Having thus described my invention, I claim:

1. In a hand loom, a rectangular frame composed of longitudinal sidewalls, endwalls extending between and secured to the ends of the sidewalls, slats extending longitudinally between said endwalls and secured to edges of said endwalls at one side of said frame, said slats being transversely spaced from each other across the frame to define longitudinal slots, said slats being formed with holes located intermediate their ends and arranged in a transverse row extending crosswise of said frame, a spindle journaled through said sidewalls at a point between said row of holes and one endwall of the frame and spaced from said slats.

2. In a hand loom, a rectangular frame composed of longitudinal sidewalls, endwalls extending between and secured to the ends of the sidewalls, slats extending longitudinally between said endwalls and secured to edges of said endwalls at one side of said frame, said slats being transversely spaced from each other across the frame to define longitudinal slats, said slats being formed with holes located intermediate their ends and arranged in a transverse row extending crosswise of said frame, a spindle jour-

nalled through said sidewalls at a point between said row of holes and one endwall of the frame and spaced from said slats, and means acting between one of said sidewalls and said spindle for releasably locking said spindle in selected rotated positions of said spindle.

3. In a hand loom, a rectangular frame composed of longitudinal sidewalls, endwalls extending between and secured to the ends of the sidewalls, slats extending longitudinally between said endwalls and secured to edges of said endwalls at one side of said frame, said slats being transversely spaced from each other across the frame to define longitudinal slots, said slats being formed with holes located intermediate their ends and arranged in a transverse row extending crosswise of said frame, a spindle journaled through said sidewalls at a point between said row of holes and one endwall of the frame and spaced from said slats, and means acting between one of said sidewalls and said spindle for releasably locking said spindle in selected ro-

tated positions of said spindle, consisting of a disc keyed on the spindle and provided with circumferentially spaced holes, and a locking pin transverse said one sidewall and engageable in the holes of the locking disc.
